DESIGN FOR A HAT

Renabelle Lonnie Reese, Washington, D. C.

Application June 2, 1942, Serial No. 107,679

Term of patent 7 years

To all whom it may concern:

Be it known that I, Renabelle Lonnie Reese, a citizen of the United States, residing at Washington, in the District of Columbia, have invented a new, original, and ornamental Design for a Hat, of which the following is a specification, reference being had to the accompanying drawing, forming part thereof, wherein,

Fig. 1 is a side elevational view of a hat showing my design.

Fig. 2 is a top plan view of the hat shown in Fig. 1, and

Fig. 3 is a rear perspective view of the hat shown in Fig. 1 with a wearer thereof being shown in dot and dash lines.

The essential features of the design reside in the parts shown in full lines in the drawing.

I claim:

The ornamental design for a hat, as shown and described.

RENABELLE LONNIE REESE.
